(57) **CLAIM**

The ornamental design for a portion of an electronic mouse, as shown and described.

DESCRIPTION

FIG. 1 is a front perspective view of a portion of an electronic mouse showing our new design;

FIG. 2 is a rear perspective view thereof;

FIG. 3 is a right side view thereof;

FIG. 4 is a left side view thereof;

FIG. 5 is a top view thereof;

FIG. 6 is a front view thereof; and,

FIG. 7 is a rear view thereof.

The broken line showing of various regions, including the unshaded areas therein, is for illustrative purposes and forms no part of the claimed design. The unshown bottom of the electronic mouse forms no part of the claimed design.
